Primary Examiner—Mitchell I. Siegel*Attorney, Agent, or Firm*—Howard & Howard[57] CLAIM

I claim the ornamental design for a golf putter head, as shown and described.

The broken line showing of a fragmented shaft is for illustrative purposes only and forms no part of the claimed design.
